LIFTING APPLIANCE

Julio Villars, Versoix-Geneva, Switzerland

Application July 12, 1955, Serial No. 521,523

Claims priority, application Switzerland July 14, 1954

2 Claims. (Cl. 187—17)

Lifting appliances are known for instance to render easier the loading of packages on lorries. This kind of appliance comprises generally a motor actuating a platform carried by a movable frame. Said frame is guided vertically by means of guiding members fastened on the one hand on the sides of said frame and on the other hand on the walls of a pit entirely closed by said platform when this platform is in its lower position. Said kind of appliance presents several drawbacks. Particularly the cost is relatively high as the driving motor of the platform must be housed in an excavation especially made for it. Further, the walls of the pit must be very solid in order to obviate any deformation of the guiding members of the movable frame carrying the platform.

Besides, this kind of appliance comprises generally a mass suspended by a flexible member connected mechanically to the shaft of the driving motor of the platform. The mechanical connection is made in such a manner that said mass will be lifted when the platform goes down. When the platform goes up, said mass lightens the load on the driving motor. However, generally the weight of said mass does not exceed the weight of the movable frame of the platform, that is to say that this weight is limited to the counterbalancing of said platform, in order to obviate the considerable costs of a mass of several tons.

The present invention has for an object a lifting appliance comprising a platform carried by a movable frame actuated by a motor and which is characterized by the fact that it comprises an auxiliary motor which constitutes an accumulator of energy storing energy during the descending of the platform and restoring said energy during the lifting of said platform.

The annexed drawing shows schematically and by way of example two forms of construction of the lifting appliance object of the invention.

Fig. 1 is a perspective view of the first form of construction of the appliance, the platform being in its lower position.

Fig. 2 is a perspective view, the platform being in its lifted position, certain parts being cut away for clarity.

Fig. 3 is a cross section.

Fig. 3a is a fragmentary horizontal sectional view.

Fig. 4 is a view of a detail.

Figs. 5 and 6 are partial side and plan views of a modified form of construction of the auxiliary motor.

According to Figs. 1 to 4 of the attached drawing, the appliance comprises a platform 1 carried by a movable frame 2 having the general shape of a cage. The four side faces of said frame are covered with sides 3. The movable frame 2 is positionable within a pit 4 and is carried by means of four flexible carrying members 5. Said members 5 are constituted by cables, one extremity of each of which is fastened to a central winding drum 6, whilst the other extremity of each cable is fastened to the lower extremity of four uprights of the movable frame. Said carrying members pass over sheaves 8 rotating free on axes 9 rigidly fastened on the upper ex-

2

tremities of four posts 10 fastened on the bottom 11 of the pit and located in the four corners of said pit 4.

The drum 6 is driven by a vertical driving shaft 12 connected by a reducing gear, housed in a casing 13, to the shaft of an electric motor 14. Said shaft 12 comprises a prolongation 15 which constitutes the shaft of an auxiliary motor 16. Said motor 16 comprises springs wound up on themselves and one of the extremities of each of which is fastened to the shaft 15 whilst their other extremities stay against central columns 17 fastened on the bottom of the pit and carrying the casing 13 of the reducing gear. Distance pieces 18 connect rigidly the upper extremity of each post 10 to the casing 13 and to the columns 17. Said distance pieces constitute with the posts and the columns an internal fixed frame.

When the platform is in its upper position (Fig. 2) its top is located for instance at the level of the deck of truck (Fig. 2).

When the electric motor 14 is energized by lowering of a control member M of a control casing C, the user causes the lowering of the platform. The movable frame enters inside the pit. During said lowering stroke of the platform, the electric motor 14 winds up the springs and consequently winds up the auxiliary motor. When the top of the platform reaches the level of the ground, an abutment 19 carried by the movable frame actuates the control member 20 of an end stroke circuit breaker 21 and causes the stopping of the electric motor and thus the stopping of the whole appliance.

When the user desires to cause the rising of the platform he lifts up the control member M of the control box C in order to energize the electric motor. From then on, said motor 14, helped by the auxiliary motor 16, causes the lifting of the platform by means of the winding up of the carrying cables on the multiple drum 6. When the platform reaches its upper position, an abutment 22 actuates the control member 23 of an end stroke circuit breaker 24.

The tests effectuated, have shown that the auxiliary motor 16 causes a large reduction in the power of the electric motor 14 which is normally necessary to raise a given load, corresponding to the load for which the platform is calculated, to a given height in a given time. Said auxiliary motor, wound up by the main motor and partly by the load carried by the platform during the lowering of said platform, constitutes in fact an accumulator of energy. The energy accumulated by this auxiliary motor is used to lift a part of the load which the platform may carry.

The mechanical connection between the shaft of the motor 14 and the winding drums 6, comprises a worm 26 meshing with a worm wheel 25. The pitch of said worm is chosen in such a manner as to realise an irreversible transmission, that is to say that the worm wheel subjected by the intermediary of the cables, to the action of the weight of the platform and of the load carried by said platform, may not in any case cause a rotation of said worm.

An advantage of the described appliance is that the shaft 15 of the auxiliary motor carries the multiple winding drum 6. It follows that the members of the reducing gear 13 do not carry a great part of the load carried by the platform. Consequently, the wear of the members of the reducing gear is far less than in the known appliances and their life is increased.

The horizontality of the platform is ensured by the carrying cables, even if the load is located unsymmetrically on the platform. Each post 10 carries further a guiding member 27 cooperating with guides constituted by the uprights forming the corners of the frame.

From the foregoing it results that the pit necessary for the housing of the platform and of its movable frame,

houses also all the elements and members necessary for the actuation of said platform and that further, the walls of said pit do not carry any rail or other guiding member. This peculiarity presents in practice very great advantages and reduces in a great way the cost of the appliance, for the walls of the pit need no longer be specially built and made in order to allow the fastening of such guiding members. Said walls may not be absolutely vertical nor absolutely plane, without hindering the good working of the appliance. Besides, the total volume of the pit necessary to house the described appliance is approximately equal to the volume of the movable frame of the platform. On the other hand, in the known appliances, the volume of the pit is far greater (two to three times) than the volume of the movable frame of the platform, that is to say than the volume which must be moved.

The energy accumulator constituted here by a spiral spring motor mechanically connected to the winding drum, may be substituted by any other kind of spring motor, such as a twisting spring for instance. The four carrying cables may be substituted by a carrying and pulling cable attached on the one hand to the lower part of an upright and on the other hand to the winding drum, and by three funicular cables of a constant length. One of the extremities of each of said three cables may be attached to the foot of one of the columns and the other extremity of each of the funicular cable, may be fastened to the extremity of one of the three other uprights, after having passed over a rotatable guide carried by the corresponding column. Such a disposition of pulling carrying cables and of funicular carrying cables, is already known and used for instance in lifting appliances for touring cars and described for instance in the U. S. Patent No. 2,640,562.

Figs. 5 and 6 show partially a modified form of construction of an appliance according to the invention. The auxiliary motor 16 comprises a cylinder 28 in which slides a piston 29. Said piston is mechanically connected, by means of a toothed rack 30 and a pinion 31, to the shaft 15. A duct 32 connects said cylinder to a bottle partially filled with liquid.

When the platform goes down, the piston penetrates inside the cylinder and compresses the gas contained in the upper part of said bottle 33. Said gas, perfectly elastic, restores the stored energy during the next actuating upwards displacement of the platform.

Two forms of execution of an appliance object of the invention have been described here by way of examples, but it goes without saying that several variants may be realised, adapted to the several requirements prescribed in each particular case.

From the foregoing one may easily see that the appliance object of the invention is of a cost which is much cheaper than the cost of an appliance of a known kind.

Besides, the consummation of electric energy and thus the power of the motor which must be foreseen, is much

less than in the known appliances, for the main electric motor is of a power approximately equal to half of the power which would be necessary, in the absence of an auxiliary motor, in order to raise a given load to a given height in a given time. This particular point represents also a great advantage of the described appliance.

I claim:

1. In a lifting appliance, a platform having frame means depending therefrom, said platform and frame means being adapted to be raised from and lowered into a pit, sheaves positioned in the upper part of said pit adjacent said frame means, motive means, transmission means drivingly connected with said motive means, means supporting said motive means and said transmission means in said pit, said transmission means having a central vertical output shaft having a drum thereon, cables connected to said drum extending over said sheaves and attached to the lower ends of said frame means, and an energy accumulator in said pit, a downward prolongation 10 of said output shaft, said accumulator being operatively connected to said prolongation of said output shaft of said transmission means; whereby said motion means, transmission means, support means, drum, and energy accumulator have a combined vertical height no greater than the height of said frame means.

2. In a lifting appliance, a platform having frame means depending therefrom, said platform and frame means being adapted to be raised from and lowered into a pit, sheaves positioned in the upper part of said pit 20 adjacent said frame means, motive means, transmission means drivingly connected with said motive means, means supporting said motive means and said transmission means in said pit, said transmission means having an output shaft having a drum thereon, cables connected to 30 said drum extending over said sheaves and attached to the lower ends of said frame means and an energy accumulator in said pit, a downward prolongation of said output shaft of said transmission means, said energy accumulator comprising spring means having one end thereof 40 attached to said downward prolongation of said output shaft and the other end anchored to a fixed object, whereby said motive means, transmission means, support means, drum and spring means of said energy accumulator have a combined vertical height no greater than 45 the height of said frame means.
